[57] CLAIM

The ornamental design for a composite tire and tire element,
as shown.

DESCRIPTION

FIG. 1 is a reduced perspective view of a composite tire and tire element, showing my new design, the broken line showing of the tire is for illustrative purposes only to indicate that the tire comprises multiple similar tire elements disposed in a circle, and forms no part of the claimed design; FIG. 2 is a side perspective view of the tire element of FIG. 1;

FIG. 3 is a top perspective from above and in front of the tire element of FIG. 1;

FIG. 4 is a top perspective view from above and behind the tire element of FIG. 1;

FIG. 5 is a side view of the other side of the tire element of FIG. 2;

FIG. 6 is a top plan view of the tire element of FIG. 1;

FIG. 7 is a bottom plan view of the tire element of FIG. 1; and,

FIG. 8 is a side elevation of the tire element shown in FIG. 1, in the direction of FIG. 2.
